UNITED STATES PATENT OFFICE

2,307,422

COOLING SYSTEM FOR BUILDINGS

Robert W. Richards, Denver, Colo.

Application September 12, 1940, Serial No. 356,465

3 Claims. (Cl. 257—8)

This invention relates to an apparatus and system for cooling buildings and has for its principal object the provision of a cooling system which will employ the steam radiators that are ordinarily employed for heat, as a cooling unit to cool the rooms of a building during hot weather.

Other objects of the invention are to provide means for gathering and employing the condensation from the cooling units to wash and clean incoming air; to employ the ordinary steam heating pipes as a jacket for insulating and protecting the piping conveying the cooling medium; to provide means for admitting air from the exterior and discharging air from the interior in which the heat of the incoming air will be transferred to the outgoing air so as to reduce the accumulation of outside heat to a minimum; and to provide a system and mechanism which will not corrode the steam heating piping and equipment.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a fragmentary vertical section through a typical building illustrating the invention placed therein.

Fig. 2 is a plan view of the radiator portion of the invention.

Figs. 3 is an enlarged, fragmentary, longitudinal section through a radiator and its housing, taken on the line 3—3, Fig. 4.

Fig. 4 is a cross section through a radiator, taken on the line 4—4, Fig. 3.

Fig. 5 is a fragmentary plan view, partially in section, of a heat-exchanging air conduit employed in the invention.

In Fig. 1, various typical parts of a building and its steam heating plant are designated by numerals as follows: basement 10, outer wall 11, floors 12, heating boiler 13, steam main 14, main steam valve 15, radiator return piping 16, steam radiators 17, return valve 24, radiator valves 31, and radiator traps 56.

The present invention makes use of the present steam equipment for cooling purposes in warm weather. This is accomplished by installing, in the basement 10, a refrigeration unit, designated

in its entirety by the numeral 18, of any suitable type. The refrigeration unit expands its refrigerating fluid into a cooling coil 19 which is installed in an adjacent cooling tank 20. A second compressor unit 21 is installed in the basement with its intake connected into the return line 16 of the steam heating system by means of a moisture trap 44 and a by-pass pipe 22 controlled by means of a valve 23.

Any suitable gaseous compound or element may be employed in this system as the heat transfer medium. It is preferred, however, to employ a non-oxidizing and non-corrosive gas such as helium. Helium is highly satisfactory for this purpose since it has no corrosive effects on the piping or radiators and since it has no harmful effects on human beings should a leak develop in the system.

Air could be employed, but when using air, there is a tendency to accelerate corrosion and oxidation on the steam radiator equipment from the moisture therein. Whatever is used, however, will be herein designated as the cooling medium.

25 The cooling medium is compressed in the compressor 21 and forced under pressure through a pressure pipe 25, controlled by a valve 26, into the cooling tank 20. The chilled cooling medium flows from the tank 20 through a cooling main 27 controlled by a main valve 28. The cooling main 27 is of relatively small pipe or tubing and passes directly into the interior of the steam main 14 through any suitable reducing pipe fitting 29. It continues through the interior of the main to each of the steam radiators 17 in the building. Adjacent each radiator, the cooling main exits from the steam main through a suitable packed fitting 30 placed ahead of the radiator control valve 31.

30 An expansion tube 32 is extended throughout the length of the radiator 17. This tube may be inserted through a separate opening in the radiator or may be inserted through the same opening that the steam enters the radiator. The latter method is illustrated in Fig. 1. The cooling main is connected to the expansion tube 32. The flow to the latter is controlled by a cooling valve 33. The expansion tube 32 is provided within the radiator with a series of very small discharge orifices. There is preferably one orifice directed into each of the sections of the radiators 17 as indicated at 34, Fig. 6.

The operation of the system as thus far described is as follows: The main steam valve 15, the return valve 24, and the radiator valves 31

are closed. The valves 23, 26, 28, and 33 are opened. The refrigeration unit cools the cooling coil 19 and, of course, cools the entire interior of the cooling tank 20. The cooling medium under high compression flows through the interior of the tank 20 and thence discharges through the cooling mains 21 by means of which it is carried to the various radiators in the building. At each radiator, this cold, highly compressed, gaseous medium is expanded at each of the orifices 34 into each of the cells of the radiators 17.

The expanded gases are drawn from the radiators through the return piping 16 by the suction of the compressor 21. This maintains a partial vacuum in each radiator which facilitates the expansion of the cooling medium and increases the cooling efficiency. Each radiator in the building, therefore, will quickly drop to an exceedingly low temperature.

The radiator temperature is so low that it will create frost and ice on the radiator from the natural humidity of the air in the building. Some means must therefore be provided to handle this condensate. This is accomplished by enclosing each radiator in a housing 35 having air discharge ports 36 adjacent its top. Air is constantly forced into the housing 35 by means of a suitable electrically operated blower 37 which communicates with the bottom of the housing through a suitable air conduit 38.

In some installations the circulation of the air through the housing will be sufficient to remove the frost and ice from the radiator and maintain the room air at the proper humidified point.

In other installations where the natural air is very humid, there will be a constant dripping of water from the radiator 17. This water is collected in a collecting pan 39 at the bottom of each housing 35. The water level in the pan is controlled by means of a valve float 40 which, when it rises to a certain predetermined point, opens a drain valve 41 to a drain pipe 42. The drain pipe from each radiator opens into the return piping 16 from that radiator and is controlled by means of a suitable water valve 43. The returning water from the return piping 16 is separated and collected by the trap 44 in the basement, where it is removed from the flow of the refrigeration medium. By such an arrangement, the condensate from the radiator which is constantly removed results in a dehumidifying of the room air.

In very dry climates, it may be desirable to return a portion of the moisture of the air. This is accomplished by connecting the air conduit 38 into the drain pan 39 below the water level thereof so that the air can bubble up through the water. The bubbles are broken by a first splash screen 45 positioned immediately above the water in the pan 39 and by a second splash screen 46 positioned mid-way in the height of the housing 35. The first screen prevents the water from splashing over the top of the pan. The second screen removes any drops of water from the air flow before it discharges from the ports 36. The air is still further dehumidified by contact with cold radiator surface.

In exceedingly dry climates there will not be sufficient condensate on the radiator to maintain the pan 39 filled. In such cases a water pipe 47 is installed to each of the pans 39. This pipe may connect with the city water system and may be controlled by the float 40, which also controls the drain valve 41, through the medium of a needle valve 48 positioned above the float so that

when the latter lowers to a predetermined point, as shown in Fig. 4, it will close the drain valve 41 and open the needle valve 48 to maintain a predetermined water level in the pan 39.

5 It is preferred to enclose the entire float and drain valve mechanism in a suitable collecting screen 49 to prevent accumulating debris from clogging the valve.

As thus far described, the system has been designed 10 for recirculation of the room air. It is also provided with means for intaking exterior air. This is accomplished by forming air intake openings 50 through the exterior wall 11 of the building and connecting these openings with the intakes of the blowers 37.

A suitable flap valve 51 is employed to control the opening 50 and also an interior intake opening 52 to the interior of the room. Thus, by adjusting the valve 51, either or both interior or exterior air may be admitted to the blower 37.

Naturally, when additional air is forced into the room surplus air must be allowed to exit from the room. The exiting air is cold and the incoming air is warm. Therefore, there is an expensive 25 loss of refrigeration between the two flows. A means is provided, therefore, to exchange the heat of the incoming air to the cold outgoing air.

This is accomplished by means of a heat-exchanging conduit 61 which is divided into a plurality of parallel passages by means of longitudinal partitions 53 extending from the opening 50 to the blower 37. The partitions are preferably provided with heat exchange fins 54. The alternate passages are intake passages and communicate between the openings 50 and the intake of the blower 37 for incoming air. Each intermediate passage is an exhaust passage and communicates between the opening 50 and ports 55 opening 40 to the room to accommodate the exiting air from the room. The warm incoming air will transfer its heat to the fins 54 and partitions 53 and this heat will be collected by the outgoing air and carried from the room with very little loss 45 of efficiency.

The heat which is removed from the rooms is radiated from the compressor 21 and from the refrigerating unit 18. This heat may be conducted away by enclosing these units in suitable 50 enclosing housings from which the heat may be conducted to the exterior of the building. As illustrated, the heated air from these units is conducted from the basement 10 into the smoke stack 57 of the heating boiler 13 through an intake 55 58 controlled by means of a suitable damper 59. The stack carries the hot air to the exterior of the building. Additional air is admitted to the basement from the exterior in any desired way.

60 While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. Means for cooling a room in which a steam radiator is employed and having a steam pipe for conducting steam to said radiator comprising: a refrigerating unit for refrigerating a gaseous, cooling medium; a conduit for said medium extending to a position adjacent said radiator through the interior of said steam pipe; means for compressing said refrigerated cooling medium

in said conduit; and means for expanding said chilled medium within said radiator.

2. A refrigerating system for buildings of the type having steam radiators and steam mains for conducting steam to said radiators comprising: a refrigeration unit for refrigerating a gaseous cooling medium; a cooling chamber arranged to be cooled by said refrigeration unit; a compressor for forcing a compressed gaseous cooling medium through said cooling chamber; means for conducting said chilled cooling medium to said radiator; means for expanding said compressed cooling medium within said radiator; a conduit for returning the expanded cooling medium to said compressor, said first conduit being positioned within the steam mains; and a

5 valve for controlling the first conduit independent of the steam mains.

3. In a steam heating system for buildings having steam radiators with steam mains leading to said radiators and drain lines leading from said radiators, means for circulating a cooling medium through said radiators comprising: a plant for refrigerating said medium; a conduit extending from the refrigerating plant to the radiators in the hollow interiors of the said steam mains; and a suction device connected to said drain lines for withdrawing the cooling medium therefrom after it has passed through said radiators and returning same to said refrigeration plant.

ROBERT W. RICHARDS.
